CLAIM

The ornamental design for a reduction gear for servo motor, as shown and described.

DESCRIPTION

FIG. 1 is a perspective view as viewed from the front of the reduction gear for servo motor showing our new design;

FIG. 2 is a perspective view as viewed from the rear of the reduction gear for servo motor of FIG. 1;

FIG. 3 is a perspective view as viewed from the bottom of the reduction gear for servo motor of FIG. 1;

FIG. 4 is a front view of the reduction gear for servo motor of FIG. 1;

FIG. 5 is a rear view of the reduction gear for servo motor of FIG. 1;

FIG. 6 is plan view of the reduction gear for servo motor of FIG. 1;

FIG. 7 is a bottom view of the reduction gear for servo motor of FIG. 1;

FIG. 8 is a right side view of the reduction gear for servo motor of FIG. 1; and,

FIG. 9 is a left side view of the reduction gear for servo motor of FIG. 1.

The broken lines of FIGS. 1-9 depict portions of the reduction gear for servo motor which form no part of the claimed design.
